CLAIM

The ornamental design for a clock with removable frame, as shown and described.

DESCRIPTION

FIG. 1 is a top, front and right side perspective view of a clock with removable frame showing my new design;

FIG. 2 is a front elevation thereof;

FIG. 3 is a top plan view thereof;

FIG. 4 is a right side elevation thereof;

FIG. 5 is a rear elevation thereof;

FIG. 6 is a bottom plan view thereof;

FIG. 7 is a top, front and right side perspective view showing the clock with removable frame in an exploded condition; and,

FIG. 8 is a rear elevation of the frame shown alone for clarity of illustration.
